(57) CLAIM

The ornamental design for a handbag with strapping, as shown.

DESCRIPTION

FIGS. 1-8 show an embodiment of the handbag with strapping of my design;

FIG. 1 is a perspective view of a handbag with strapping showing my design taken from a top left side;

FIG. 2 is a front perspective view thereof;

FIG. 3 is a rear perspective view thereof;

FIG. 4 is a right perspective view thereof;

FIG. 5 is a left perspective view thereof;

FIG. 6 is a top perspective view thereof;

FIG. 7 is a bottom perspective view thereof; and,

FIG. 8 is perspective view thereof taken from a top left side and showing the handbag with strapping in an open position. The broken lines showing stitching and portions of the handbag are for the purposes of illustrating environment and forms no part of the claimed design.
